UNITED STATES PATENT OFFICE.

ALVA J. FISHER, OF EVANSTON, ILLINOIS, ASSIGNOR TO HURLEY MACHINE COMPANY,
OF CHICAGO, ILLINOIS, A CORPORATION OF ILLINOIS.

VACUUM-CLEANER.

1,286,571.

Specification of Letters Patent.

Patented Dec. 3, 1918.

Application filed October 23, 1916. Serial No. 127,247.

To all whom it may concern:

Be it known that I, ALVA J. FISHER, a citizen of the United States, residing at Evanston, in the county of Cook and State 5 of Illinois, have invented certain new and useful Improvements in Vacuum-Cleaners, of which the following is a specification.

My invention relates to vacuum cleaners and the object thereof is to provide a simple 10 and efficient buffer device for the front end thereof, particularly the nozzle casing of the cleaner, which is of the suction fan type.

In the drawing Figure 1 is a front elevation of my vacuum cleaner, with the buffer 15 device thereon; Fig. 2 a side elevation thereof; and Fig. 3 a sectional detail on the line 3-3 of Fig. 1.

As the invention pertains merely to the nozzle casing and the buffer thereon, the construction of the cleaner need not be described, excepting to say that the fan is contained within the casing 1 and draws the air up through the interior of the nozzle casing 2, and discharges it at the outlet 3. The lower horizontal edges of this nozzle 25 casing are turned outwardly and rolled over into the form of tubes, the forward one of which, indicated at 2^a, is utilized as a support or bearing for the shaft 4 of the small 30 rollers 5 at the opposite ends thereof, such shaft being offset at 4^a on the inner sides of these rollers.

The buffer device consists of a strip 6 of resilient material, such as rubber, and preferably rectangular in cross-section, as shown in Fig. 3. This strip is held projected forwardly from the front side of the nozzle casing at a point between the rollers 5 and extending in a plane beyond the latter. As 40 shown in detail in Fig. 3, this flexible strip is held in place by means of another strip 7, preferably of metal and U-shaped in cross section to form a channeled retainer. This

metallic retainer strip rests upon the top edge of the tube 2^a substantially on the plane of the 45 roller axes and is welded thereto and to the nozzle casing as indicated at 8. This tube therefore forms a support not only for the shaft 4 but also a base for this metallic strip 7. The flexible strip is received within the 50 metallic strip and in order to hold the same therein the outer edges of the metallic strip are restricted or inturned slightly so as to grip or compress the strip 6 to thereby hold it in place for all practical purposes, but 55 without preventing its removal by positive force whenever desired, so that such strip can be removed or renewed when desired.

I claim:

1. In a vacuum cleaner the combination 60 of a suction nozzle casing having its lower edge curled into a tube projecting beyond the adjacent lower portion of the front wall of the nozzle, a shaft mounted in said tube and having rollers mounted thereon; a channeled front-opening retainer mounted to bear downwardly on said tube and rearwardly against the front wall of the nozzle, and a flexible buffer strip supported by said retainer and projecting forward beyond the 70 nozzle structure and the rollers.

2. In a vacuum cleaner the combination of 75 a suction nozzle casing having its front lower edge outwardly and upwardly curled to form a projecting tube along the nozzle, a shaft substantially filling said tube, rollers on the end of said shaft, a U-shaped front-opening retainer-strip resting on the tube and bearing at its rear, closed edge against the front wall of the nozzle above the tube and secured 80 rigidly to both thereof throughout its length, and a buffer strip carried by the retainer strip projecting from the front thereof to a line in advance of the rollers.

ALVA J. FISHER.
